UNITED STATES PATENT OFFICE.

JOHN BENJAMIN NICHOLSON, OF SCHENECTADY, NEW YORK.

HAIR-CRIMPER.

SPECIFICATION forming part of Letters Patent No. 593,679, dated November 16, 1897.

Application filed April 12, 1897. Serial No. 631,831. (No model.)

To all whom it may concern:

Be it known that I, JOHN BENJAMIN NICHOLSON, a citizen of the United States, and a resident of Schenectady, county of Schenectady, and State of New York, have invented certain new and useful Improvements in Devices for Curling the Hair or Mustache, of which the following is a specification, reference being had to the accompanying drawings, forming a part thereof, in which similar letters of reference indicate corresponding parts.

This invention relates to devices for curling the hair or mustache; and it has for its object to provide a simple and improved device of this character which will possess advantages in point of convenience, effectiveness, ease of operation, inexpensiveness, and general efficiency.

20 In the drawings, Figure 1 is a face view showing the device in closed or folded position. Fig. 2 is a side view of the device in the same position. Fig. 3 is a perspective view of the device, showing it in open position ready for the reception of the hair. Fig. 4 is a detail transverse sectional view. Fig. 5 is a detail perspective view showing the modified form of connection between the spring-handle and body of the device.

30 Referring to the drawings, A designates the body portion of the device, which comprises a cylindrical member a, to one end of which is hinged, as at a', a concave leaf a². The hinged member a² is adapted to rest over and partially surround the member a when the device is in closed position, as shown in Figs. 1 and 2. At the free end of the hinged leaf a² it is provided with spring side walls a³ a³, which are adapted to bind or clamp the 40 sides of the cylindrical member a to retain the parts together, and the end of the member a² is provided with a projecting joint a⁴, which may be readily engaged with the finger-nail to facilitate the operation of disengaging the clamping connection between the members a² and a.

To the body portion A of the device is connected at the hinged joint a' a hinged spring-loop B, which forms a handle when the body portion of the device is open for the reception of the hair and is adapted to be swung upon its hinged joint, so that its end is connected with the outer end of the member a when the device is closed. The loop B thus forms an 55 outer retaining-frame for the hair.

The member a may be provided with a projecting recessed end a⁵, into which recess the spring-loop B may be sprung. In lieu of this recessed end a knob a⁶ may be formed upon the end of the member a and be engaged by 60 a supplementary spring-loop b, provided upon the free end of the loop B, as illustrated in Fig. 5.

Projecting nibs b' b' may be provided upon the side arms of the spring-loop B, which will 65 serve to retain the device in position upon a lamp-chimney if the heating of the body of the device should under any circumstances be desired.

I form the members a and a² of the body 70 of the device of copper and the outer loop or frame B of brass, so that an electrotherapeutic action is secured when the device is in use.

The operation and advantages of my invention will be readily understood. When the device is opened to the position shown in Fig. 3, the outer spring-loop or frame B forms a handle and the hair may be wrapped around the cylindrical body member a. The hinged 75 leaf a² may then be clamped down in position upon the cylindrical member a with the hair 80 inclosed between, when the spring-loop B is carried over to the position shown in Figs. 1 and 2 and engaged with the outer end of the 85 body portion, so that it forms an outer retaining-frame.

Having thus described my invention, what I claim as new, and desire to secure by Letters Patent, is—

An improved device of the class described, comprising the body having a cylindrical member formed with a catch device at its outer end and a concave leaf in hinged connection with said cylindrical member provided at 90 its free end with spring-clamping walls or projections and a projecting nib or point, in combination with a spring-loop hinged to said body portion and adapted to be sprung into engagement with the catch devices at the 95 outer end of the cylindrical member, substantially as and for the purpose set forth.

In testimony that I claim the foregoing as my invention I have signed my name, in presence of two witnesses, this 8th day of April, 105 1897.

JOHN BENJAMIN NICHOLSON.
Witnesses:

JAMES ALLEN CROUNSE,
CHARLES S. McDONALD.
